UNITED STATES PATENT OFFICE.

CHARLES O. WHITNELL, OF KINGSLEY, IOWA.

ADJUSTING MEANS FOR SKYLIGHTS, &c.

1,260,110.

Specification of Letters Patent. Patented Mar. 19, 1918.

Continuation in part of application Serial No. 97,369, filed May 13, 1916. This application filed October 23, 1916. Serial No. 127,287.

To all whom it may concern:

Be it known that I, CHARLES O. WHITNELL, a citizen of the United States, residing at Kingsley, in the county of Plymouth 5 and State of Iowa, have invented new and useful Improvements in Adjusting Means for Skylights, &c., of which the following is a specification.

My present invention pertains to means 10 for raising and supporting skylights and the like; and it contemplates the provision of improved means for the purpose, designed more especially for use in the skylight structure constituting the subject of 15 my contemporary application filed May 13, 1916, Serial Number 97,369, of which this application is, in part, a continuation.

The present invention in all of its details will be fully understood from the following 20 description and claim when the same are read in connection with the drawings, accompanying and forming part of this specification, in which:

Figure 1, is a transverse section showing 25 the application of one embodiment of my invention and also showing the skylight in closed position.

Fig. 2 is a view at right angles to Fig. 1, and showing the skylight supported in its 30 open position.

Fig. 3 is a view like Fig. 1 of a modification.

Fig. 4 is a plan of the said modification.

The illustrated embodiment of my invention in Figs. 1 and 2 comprises a base in which is an opening surrounded by an up-standing rectangular flange 2, and hinged at 4 to said flange 2 is a skylight 1, that is designed to be swung upwardly and downwardly on the flange 2 of the base. The said skylight 1 in general may be of any suitable construction. In accordance with my present invention it is equipped with a longitudinal central bar 16. The said bar 40 16 is spaced from the skylight and is provided with arms at its end through the medium of which it is fixedly connected with the skylight. Receiving and movable on the said bar is the eye 18 of a vertically 45 swinging arm 17. The said arm 17 is carried at one end of a horizontal rock-shaft 10 which is journaled in a bearing 19 on the base flange 2, and at its opposite end the said shaft merges into an arm 20 which, in 50 55 turn, terminates in a handle 21. By virtue

of this construction, it will be manifest that when the parts are relatively arranged as shown in Fig. 2, the arm 17 will serve to maintain the swinging section or skylight in raised position and without liability of 60 said section casually falling. This is due to the fact that the arm 17 brings up against the arm of the bar 16 remote from the hinge as clearly shown in Fig. 2. When, however, the handle 21 is pressed toward the right in 65 Fig. 2, the swinging section or skylight will be lowered to its closed position and will be controlled incidental to the downward movement so as to preclude the possibility of breakage. It will also be manifest that 70 when the swinging section or skylight is in its closed position and it is desired to open the same, for ventilating purposes, it is simply necessary to apply sufficient effort to swing the handle 21 in Fig. 2 toward the 75 left, whereupon the swinging section will be raised to and secured in position shown in said figure.

In the modification shown in Figs. 3 and 4, the skylight or swinging section 1^a is 80 equipped with two bars 16^a. The said bars 16^a are spaced from, and fixedly connected through end arms to the skylight, and are disposed in eyes 18^a on the vertically swinging arms 17^a of a horizontal rock-shaft 10^a. 85 The said rock-shaft is journaled in bearings 19^a on the upstanding flange 2^a of the base, and is equipped with a handle 20^a. The operation of this construction is similar to the construction shown in Figs. 1 and 2 and 90 need not, therefore be reiterated.

It will be noted from the foregoing that in each of the embodiments of my invention, the means employed for moving the skylight is extremely simple and inexpensive, and yet when the skylight or swinging section is adjusted to its raised position, there is no liability of the skylight or section tending to move downwardly until the adjusting means is properly manipulated. 100

It will also be noted that in both embodiments of my invention the permanent connection of the eye on the arm of the rock-shaft to the bar on the skylight permits of the adjusting means being utilized to hold 105 the skylight in closed position.

Having described my invention, what I claim and desire to secure by Letters-Patent, is:

The herein described skylight construc- 110

tion comprising a base frame having an opening and an upstanding flange surrounding said opening, a skylight hinged at one end to the outer side of said base flange and constructed and arranged to close over the same, a horizontally-disposed bearing fixed to the inner side of the base flange and arranged parallel to the hinge of the skylight, a bar extending longitudinally of and parallel to and spaced from the skylight and having end arms fixed thereto, said bar being disposed at right angles to said hinge and bearing, and a horizontal rock shaft journaled in said bearing and having an angularly-disposed handle and also having

an angularly-disposed arm extending in an opposite direction to the handle and on the end of which is an eye permanently connected with and receiving and movable on the bar of the skylight; the latter arm being arranged to bring up against that arm of the bar remote from the hinge and securely maintain the skylight in raised position. 20

In testimony whereof I have hereunto set my hand in presence of two subscribing witnesses.

CHARLES O. WHITNELL.
